ARC LAMP

Arthur Müller, Leipzig-Leutzsch, Germany, assignor to the firm Körting & Mathiesen Aktiengesellschaft, Leipzig-Leutzsch, Germany

Application December 13, 1937, Serial No. 179,522
In Germany December 24, 1936

5 Claims. (Cl. 176—53)

This invention relates to improvements in arc lamps and particularly to an arc lamp to be used with multiphase current.

It is the object of this invention to provide 5 an arc lamp having a reliable electrode regulating mechanism operable with multiphase alternating current.

It is the further object of this invention to provide a three electrode arc lamp having mechanism 10 to adjust the electrodes uniformly by use of a single electro-magnet.

It is also the object of this invention to provide a three electrode arc lamp devoid of complexity and economical to manufacture and maintain.

Further objects and advantages of the invention will be apparent from the following detailed description of the embodiments of the invention shown in the accompanying drawing, 20 wherein:

Figure 1 is an elevation view, partly diagrammatic, of an arc lamp embodying this invention.

Figure 2 is a section view showing the interengagement of gears provided for regulating the 25 position of the electrode holders.

Referring to the drawing, for the purposes of illustration, the arc lamp electrodes or carbons, three in number, are designated by the numeral 1. The electrodes 1 are supported in holders 2 and arranged to swing in vertical intersecting planes, preferably disposed about one hundred and twenty degrees apart. Three intermeshing gears 3 are supported on pivots 12, 13 and 14 carried by the lamp frame and may be arranged as 35 shown in Figure 2. One of the gears 3 is provided with two rows of teeth 15 for engaging both of the other gears, whereby all three gears may be rotated simultaneously in equal amounts. The upper end of each electrode holder 2 is pivotally connected to a gear 3, the location of the pivot being eccentric to the center of the gear. Each electrode holder 2 is also provided with a pin 16 engaging a guide slot 17 in the support for its operating gear 3.

One of the gears 3 is provided with a sprocket wheel 4 secured thereto. A chain 4a or the like extends from sprocket 4 to the core 5 of an electro-magnet. The core 5 is supported by a spring 18 of suitable tension. The electro-magnet has three coils 6, 7 and 8. Coil 6 is a potential coil, and coils 7 and 8 are oppositely connected current coils. The electrodes 1 are connected with flexible leads to suitable terminals connected through resistances 9, 10 and 11 to 55 the wires of a three phase alternating current

network R. S. T. Potential coil 6 is connected across the leads to two electrodes, and the oppositely wound current coils 7 and 8 are connected in the leads to said two electrodes.

The operation of the electrode regulating mechanism is as follows: The arcs between the tips of the three electrodes 1 are maintained uniform through the action of the electro-magnet 5 which turns the gears 3 in equal amounts to uniformly adjust the electrode holders 2 connected thereto. When the gap between the electrodes becomes too large, the change in the potential and current values causes the core 5 to be moved downwardly whereby the electrode ends of holders 2 are moved toward the arc to partially close the gap. By providing proper tension in the spring 18 supporting core 5, a balanced regulating action is secured which maintains uniform arcs.

This invention also contemplates various 20 changes and rearrangements of the apparatus shown and described, as it will be apparent to one skilled in the art that numerous variations are possible within the scope of the appended claims.

I claim:

1. In an arc lamp for three phase alternating current, the combination comprising three interengaging rotatable elements, three electrode holders disposed relatively at obtuse angles, each 30 holder being operatively connected to one of said elements and provided with a slidable pivot and guide therefor, and an electro-magnet responsive to variations in the electrical values of the arc connected to one of said elements for turning 35 each of said elements a uniform amount, whereby the gap between electrodes is regulated.

2. In an arc lamp for three phase alternating current, the combination comprising three interengaging gears arranged relatively at 120°, three 40 electrode holders disposed relatively at obtuse angles, said holders being pivotally connected to said gears and being provided with guide means, and magnetic means responsive to variations in the electrical values of the arc connected to said gears for turning the same to 45 regulate the gap between said electrodes.

3. In an arc lamp for operation with three phase alternating current, the combination comprising three intermeshing gears arranged relatively at obtuse angles, one of said gears having double teeth for engagement with each of the other gears, three electrode holders arranged relatively at obtuse angles, a slidable pivot for each of said holders and a pivotal connection 55

between each holder and a gear, an electromagnet mechanically connected to one of said gears and provided with a potential coil and two oppositely wound current coils connected to different phases, whereby the gap between said arc lamp electrodes is uniformly regulated in accordance with variations in the electrical values of the arc.

4. In an arc lamp for multiphase alternating current, the combination comprising a plurality of interengaging elements, an electrode and an electrode holder for each of said elements, each of said holders being pivotally connected to its corresponding element, guide means for said holders, and magnetic means operatively connected to one of said elements for turning each of said elements uniformly in response to varia-

tions in the electrical values of the arc between said electrodes, whereby the gap between said electrodes is automatically regulated.

5. In an arc lamp for three phase alternating current, the combination comprising three inter-engaging gears disposed relatively at obtuse angles, three electrode holders pivotally connected, respectively, to said gears, an electro-magnet having a core and having a plurality of coils connected to different current phases for regulating the position of said core, and means connecting said core to one of said gears for turning each of said gears, whereby the electrode holders are uniformly adjusted in response to variations in the electrical values of the arc. 15

ARTHUR MÜLLER.
